ATTORNEY.

UNITED STATES PATENT OFFICE.

JOHN THOMAS MAIR, OF KHANDALLAH, NEAR WELLINGTON, NEW ZEALAND.

LATCH FOR GATES AND THE LIKE.

1,324,428.

Specification of Letters Patent.

Patented Dec. 9, 1919.

Application filed April 11, 1917. Serial No. 161,172.

To all whom it may concern:

Be it known that I, JOHN THOMAS MAIR, subject of the King of Great Britain and Ireland, residing at Main Road, Khandallah, 5 near the city of Wellington, in the Dominion of New Zealand, have invented a new and useful Improvement in Latches for Gates and the like; and I do hereby declare the following to be a full, clear, and exact 10 description of the same.

This invention relates to latches for gates and the like.

The object of the invention is to provide a latch which will be certain in its action and 15 simple in construction.

In this invention a pivoted gravity catch is so constructed that the locking part thereof may be lifted for the purpose of opening the gate by operating a lever which has 20 a cam action and with which the catch interlocks. Both the lever and the catch revert to the closed position by gravity. A further feature is the construction of the lever in such a way that the action of closing the 25 gate by moving the striker past the catch brings the striker into contact with an arm of the lever hereinafter termed a trigger whereby the catch is, independently of the action of gravity, completely closed through 30 the action of the lever. When the lever is operated for the purpose of opening the gate this arrangement causes the striker to be carried forward beyond the locking position 35 of the catch, thereby not only releasing the striker from the catch but also pushing the gate open. If desired the lever may be operated by a push rod operating against the trigger whereby the gate may be opened from the outside. Provision is also made 40 for locking the latch in a closed position by means of a separate lock.

The invention is illustrated by the accompanying sheet of drawings wherein:

Figure 1 is a perspective view of the 45 latch, the striker being shown lowered.

Fig. 2 is a view in elevation of the front of the latch.

Fig. 3 is a plan of the top of the latch.

Fig. 4 is a side view in elevation of the 50 latch.

Fig. 5 is a sectional view showing the working parts of the latch in closed position.

Fig. 6 is a sectional view showing the working parts of the latch in an open posi-

tion and also showing the method of opening the latch by means of a push rod.

Referring to the drawings, 1 is the frame, 2 is the catch which is pivoted near the front and bottom of the frame, 3 is the lever which is pivoted near the rear of the frame, 60 and 4 is the striker.

The frame 1 is made with a portion of the front cut away to form the shoulder 5 upon which the lever 3 rests when the latch is closed. Holes are bored in the frame to 65 receive rivets 6 and 7 and holes 8 are bored in the flanges 9 of the frame to receive screws for fixing the latch to the post.

The catch 2 is pivoted on the rivet 6 and is formed with a projection 10 shaped as 70 shown. This projection 10 fits into a recess 11 in the lever 3. The lever 3 is pivoted on the rivet 7 and is formed with a projection 12 which fits a recess 13 and operates therein with a cam action for the purpose of opening the catch 2. The cam faces are so shaped that the pressure of the striker against the locking edge 14 of the catch brings the catch down to its locked position apart from gravity. The catch has also a 80 striking face 15 against which the striker operates and causes the catch to revolve out of the way.

The lever 3 is also provided with an extended arm 16 ending in a trigger 17 whereby the catch is, independently of gravity, completely closed by the action of the cam 12 which forces the catch downward when the striker 4 operates against it. This trigger also performs the function of pushing 90 the gate open when the lever 3 is lifted. The extended arm 16 is so shaped as to engage the catch 2 and limit its revolution in an upward direction.

In operation when it is desired to open the 95 gate the lever 3 is operated by raising the end 18 thereof. This action brings the working parts to the position shown in Fig. 6 where the catch 2 is lifted clear of the striker 4 while the trigger 17 has pushed 100 the striker beyond the locking point of the catch.

In Fig. 6 there is shown a method of operating the latch by means of a spring-operated push-rod. The rod 19 is inserted 105 through the post to which the latch is secured and has an enlarged end 20 for engaging the trigger 17. A push-button, 21 is

screwed upon the outer end of the rod while a coil spring 22 is in compression between the button and the end of a sleeve 23 as clearly shown. This spring normally allows the latch to remain closed. Upon pressing the button 21, the end of the rod pushes forward the trigger 17 raises the catch and throws the striker clear of the locking portion of the catch.

10 A shoulder 25 is formed on the top of the lever 3 so as to be co-incident with the slots 26 in the frame when the latch is closed. The bolt of a separate lock or other device inserted in the slots 26 behind the shoulder 15 25 will prevent the revolution of the lever 3 and thus lock the device.

10 The striker 4 is preferably offset or deformed to clear the trigger 17 when the gate is closed as clearly indicated in Fig. 3 and is fixed by screws in holes 27.

What I claim is:—

1. In a latch, a pivoted gravity catch, a striker adapted to operate said catch upon its closing movement, a pivoted gravity 25 lever having at its rear end a downwardly extending lever against which the striker engages, cam faces upon the upper edge of said catch, and cam faces upon the lower edge of said lever interlocking with said 30 cam faces of said catch in such a manner that the movements of said catch and said lever are synchronous, substantially as described.

2. In a latch, a frame, a gravity catch 35 pivoted near the front end of said frame and having a striking face upon its lower side, a striker adapted to raise the said catch upon its closing movement, said catch falling by gravity immediately said striker 40 has passed it and thereby retaining the striker, a gravity lever pivoted at its rear end only and near the rear of said frame said lever having at its rear end a downwardly extending lever against which the 45 striker engages, a curved recess in the upper edge of said catch, and a cam projection on the lower edge of said lever engaging said recess whereby when said lever is lifted said projection will carry the said catch 50 upward with a radial movement in order to clear the said striker, substantially as described.

3. In a latch, a frame, a gravity catch pivoted near the front end of said frame 55 and having a striking face upon its lower edge, a striker adapted to raise the said catch upon its closing movement, said catch falling by gravity immediately said striker has passed it and thereby retaining the 60 striker, a gravity lever pivoted at its rear end only and near the rear of said frame said lever having at its rear end a downwardly extending lever against which the striker engages, a curved recess in the upper edge of said catch, a cam projection

upon the lower edge of said gravity lever engaging said recess in said catch whereby the said catch and the said lever move synchronously, substantially as described.

4. In a latch, a frame, a gravity catch 70 pivoted near the front end of said frame and having a striking face upon its lower edge, a striker adapted to raise the said catch upon its closing movement, said catch falling by gravity immediately said striker 75 has passed it and thereby retaining the striker, a gravity lever pivoted at its rear end only and near the rear of said frame said lever having at its rear end a downwardly extending lever against which the 80 striker engages, a curved recess in the upper side of said catch, a cam projection upon the lower side of said gravity lever engaging said recess in said catch, a recess in the lower side of said lever, and a cam projection on said catch engaging said recess in said lever, substantially as set forth.

5. In a latch, a pivoted gravity catch, a striker adapted to operate said catch upon its closing movement, a pivoted gravity lever 90 having at its rear end a downwardly extending lever against which the striker engages, cam faces upon the upper edge of said catch, cam faces on the lower edge of said lever interlocking with said cam faces of said 95 catch in such a manner that the movements of said catch and said lever are synchronous, the rear end of said lever upon its under edge being shaped to receive the said catch and limit its revolutions in an upward direction, substantially as described.

6. In a latch, a pivoted gravity catch, a striker adapted to operate said catch upon its closing movement, a pivoted gravity lever 105 having at its rear end a downwardly extending lever against which the striker engages, cam faces upon the upper edge of said catch and cam faces upon the lower edge of said catch interlocking with said cam faces of said catch in such a manner 110 that the movements of said catch and said lever are synchronous, combined with a push-rod which engages and operates said lever, substantially as set forth.

7. In a latch, a frame, a gravity catch 115 pivoted in said frame, a striker adapted to raise said catch upon its closing movement, a gravity lever pivoted in said frame so shaped as to interlock with the said catch whereby the catch is lifted when said lever 120 is raised, and an extended arm to the rear end of said lever against which the said striker is adapted to engage whereby the said catch is returned to its closed position through the intervention of said lever, independently of gravity, substantially as set 125 forth.

8. In a latch, a pivoted gravity catch, a striker adapted to operate said catch, a pivoted gravity lever interlocking with said 130

catch in such a manner that the said catch may be lifted by operating the said lever, the rear end of said lever formed with a downwardly extending arm against which 5 the said striker engages, and a push rod in engagement with said downwardly extending arm whereby the said catch is raised by operating said rod.

9. In a latch, a pivoted gravity catch, a 10 striker adapted to operate said catch upon its closing movement, a pivoted gravity lever, cam faces upon the upper edge of said catch, and cam faces upon the lower edge 15 of said lever interlocking with said cam faces of said catch in such a manner that

the movements of said catch and said lever are synchronous, a shoulder upon said lever, and slots in said frame with which said shoulder is coincident whereby the bolt of a separate lock may be inserted in said slots 20 and behind said shoulder, substantially as set forth.

In testimony whereof I have signed my name to this specification in the presence of two subscribing witnesses.

JOHN THOMAS MAIR.
